Primary Examiner — Martie K Holtje*(74) Attorney, Agent, or Firm* — Kaplan Intellectual Property Law, LLC(57) **CLAIM**

The ornamental design for a retractable leash, as shown and described.

DESCRIPTION

FIG. 1 is a side view of a retractable leash showing the claimed design;

FIG. 2 is a rear view thereof;

FIG. 3 is a front view thereof;

FIG. 4 is a top view thereof; and,

FIG. 5 is a bottom view thereof.

The structural features depicted by broken lines in FIGS. 1, 4, and 5 have been shown for the purpose of illustrating portions of the retractable leash that form no part of the claimed design.

The claimed design of retractable leash preferably may be used for purposes of tethering, controlling, and leading small animals, typically domesticated breeds of dogs, by persons walking them.
